UNITED STATES PATENT OFFICE.

LESTER L. BROWN, OF HOUSTON, TEXAS.

TURBINE.

Application filed July 26, 1920. Serial No. 399,010.

To all whom it may concern:

Be it known that I, LESTER L. BROWN, a citizen of the United States, residing at Houston, in the county of Harris and State 5 of Texas, have invented certain new and useful Improvements in a Turbine, of which the following is a specification.

This invention relates to new and useful improvements in a turbine and has more 10 particular relation to a turbine of the internal combustion type.

One object of the invention is to provide a rotary turbine equipped with cylinders which are fixed in relation to each 15 other and which revolve around a stationary crank shaft and which are impelled by the expansive force of an explosive fluid operating against vanes, carried by the revolvable cylinders.

Another object of the invention is to provide a turbine of the character described 20 having fixed cylinders and reciprocating sleeves therein which control the intake and exhaust of the motive fluid.

A further feature of the invention resides 25 in the provision of cylinders of a novel construction which are separated into a compression and an explosion chamber, and the reciprocating sleeves of which control the intake of the motive fluid into the compression chamber and the delivery thereof 30 from said compression chamber into the explosion chamber whereby the motive fluid is confined in the explosion chamber from 35 which the force of the explosion is discharged against the impeller vanes, thereby imparting rotation to the turbine.

With the above and other objects in view 40 the invention has particular relation to certain novel features of construction, operation and arrangement of parts, an example of which is given in this specification and illustrated in the accompanying drawings, wherein:—

Figure 1 is a vertical sectional view taken 45 on the line 1, 1 of Figure 2.

Figure 2 is a transverse sectional view 50 taken on the line 2, 2 of Figure 1, and

Figure 3 is a vertical sectional view taken 55 on the line 3, 3 of Figure 2.

Referring now more particularly to the drawings wherein like numerals of reference designate similar parts in each of the figures, the numeral 1 designates a suitable framework, which is shown in fragmentary form in Figure 2, and fixed against

rotation in this frame-work there is a central intake pipe 2 which terminates in a bearing pin 3, aligned with said pipe, and formed integrally with them there is an eccentric wrist 4. Rotatably mounted upon the intake pipe 2 and the bearing pin 3, are the circular end plates 5 and 6, which are spaced apart, and between these end plates there are the radiating cylinders 7. These cylinders are secured in fixed position by means of the intervening arcuate webs 8, formed integrally with said cylinders. The outer end of each cylinder is closed by means of the head 9, and fitted within each cylinder there is a reciprocating sleeve 10. The outer end of each sleeve is closed by means of a disc 11, which fits snugly therein and which is spaced from the corresponding head 9, thus forming an explosion chamber 12 between said head and disc. Each disc 11 is anchored to its corresponding head by means of a centrally located neck 13, formed integrally with said head and disc, and threaded through each head there is a suitable spark plug 14. Within each sleeve 10 there is a piston 15. Piston rods 16 are provided, the outer ends of these rods are pivotally connected to the respective pistons 15, and their inner ends are pivotally connected to a ring 17, which operates on the wrist 4 as a bearing. As before stated, the cylinders and the end plates 5 and 6 are secured together, and these revolve around the pipe 2 and bearing pin 3, as a unit, thus causing the reciprocation of the pistons 15 in the sleeves 10 which, as obvious, revolve with the cylinders.

Keyed upon the bearing pin 3, within the end plate 6, there is an eccentric 18 having a peripheral rib, and fitted around this eccentric there is a ring 19 having an internal groove provided to receive said rib whereby the ring is held in position on the eccentric 18. The sleeves 10 are connected to said ring through the instrumentality of the actuating links 20, which are pivoted at their inner ends to the ring, and at their outer ends to said sleeves, and as the unitary structure, above described, revolves, the sleeves 10 are reciprocated back and forth in their respective cylinders. Each cylinder is provided with an intake port 21, and each sleeve is provided with an intake port 22. Upon suction stroke of either piston 15 the corresponding sleeve moves inwardly, through the instrumentality of

the eccentric 18, bringing said ports into registration and admitting the explosive fluid into the compression chamber within said sleeve. Before the compression stroke 5 of said piston has begun, the eccentric 18 has operated to move said sleeve outwardly to close the intake 21 and thus confine the explosive fluid within said compression chamber. The motive fluid is admitted by 10 suction through the inlet pipe 2 into the chamber, enclosed between the end plates 5 and 6, and said fluid is then admitted, as explained, into the compression chamber. Each sleeve 10 is also provided with an ob- 15 long port 23, somewhat longer than the thickness of the corresponding disc 11, and upon compression stroke of the piston, the sleeve 10 has been moved outwardly into position so that the compression chamber 20 and explosion chamber are connected through said port 23 and the explosive fluid is driven by said piston through said port 23 into the combustion chamber and there- upon, prior to the explosion, the sleeve 10 25 is again moved inwardly, carrying the port 23 out of connection with the explosion chamber and thereby closing said chamber. The eccentric 18 is so disposed relative to the wrist pin 4 as to bring about this cycle 30 of movement of the sleeve 10 in uniform succession with relation to the movements of the pistons 15. Leading from each explosion chamber through the wall of the cylinder and continuing through the end 35 plate 6, are the discharge ports 24, and upon its back stroke, the sleeve 10 uncovers these ports at the instant of the explosion and the explosive fluid is driven with great force through said ports 24, against the sta- 40 tionary vanes 25.

These vanes are formed on the inner face of a stationary annular casing 26, and are alternately arranged with respect to the co-acting vanes 27, which are formed in- 45 tegally with the annular support 28 fastened to the plate 6. The casing 26, beyond said blades is formed into a circular cham- ber 29 from which the exhaust pipe 30 leads.

The expending gas strikes against the 50 stationary vanes 25 and is thereby diverted against the movable vanes 27 and the force of the explosion causes the rotation of the support 28 and of the turbine to which said support is attached.

55 It is to be observed that the pistons 15 and sleeves 10 of the respective cylinders are timed to operate successively, thus causing successive explosions to occur in the respective chambers 12, thus imparting to the mov- 60 able impeller blades successive impulses of the explosive fluid and driving the turbine at a continuous uniform rotation.

A suitable driving shaft 31 is secured to the end plate 6 and operates in the bearing 65 32 carried by the frame-work. This shaft

is rotated as the turbine revolves and through it power may be transmitted.

What I claim is:

1. A turbine including a plurality of ro- tating cylinders each having a discharge port, pistons reciprocable in the cylinders, an eccentric bearing around which the cylinders revolve, connecting rods each pivoted at one end to its corresponding piston and at its other end to said bearing, stationary vanes against which the motive fluid is dis- charged from said ports, and vanes which are fastened to the cylinders against which the motive fluid is deflected by said sta- tionary vanes thereby imparting rotation to them and to the cylinders with which they are connected.

2. A turbine including a plurality of cyl- inders, a transverse partition in each cyl- inder separating it into a compression cham- ber and an explosion chamber, each cylinder having an intake port leading into the com- pression chamber and an exhaust port lead- ing from the explosion chamber, a sleeve fitted within each cylinder and provided with an intake port and an outlet port, a piston reciprocable in each sleeve, an eccentric bearing around which the cylinders re- volve, connecting rods pivoted at one end to said bearing and at their other ends to said pistons, whereby said pistons are re- ciprocated as said cylinders revolve around said bearing, means for reciprocating said sleeves to successively open and close said intake port, to communicate said outlet port with said compression and explosion cham- bers, to cut off said communication and then open said exhaust port, impeller blades se- cured to and rotating with said cylinders, fixed impeller blades coating with said ro- tatable blades, said fixed blades being posi- tioned to receive the motive fluid from the outlet ports and divert it against the ro- tatable blades.

3. A turbine including a plurality of radi- ating revolving cylinders, each provided with an intake and an exhaust port, im- peller vanes fastened to the cylinders, a recip- rocating sleeve in each cylinder arranged to control said ports, a transverse partition be- tween said ports, normally separating each cylinder into a compression and an explosion chamber, each sleeve having a port, con- trolled by said partition, through which said chambers are, at times, connected, an eccentric bearing, pistons reciprocable in said sleeves, means connecting said pistons to said bearing through which the pistons are recip- rocated as the cylinders revolve, means for reciprocating said sleeves, fixed vanes against which the motive fluid is projected from the exhaust ports and by which said fluid is diverted against the vanes fastened to the cylinders to rotate the latter.

4. A turbine including a plurality of

- radiating revolving cylinders, each provided with an intake and an exhaust port, a reciprocating sleeve in each cylinder arranged to control said ports, a transverse partition between said ports, normally separating each cylinder into a compression and an explosion chamber, each sleeve having a port, controlled by said partition, through which said chambers are, at times, connected, an eccentric bearing, pistons reciprocable in said sleeves, means connecting said pistons to said bearing through which the pistons are reciprocated as the cylinders revolve, means for reciprocating said sleeves, impeller vanes fixed with respect to the cylinders, stationary vanes against which the motive fluid is discharged through said exhaust ports and by which the force of the explosion is driven against the first mentioned vanes to rotate them.
5. A turbine including a plurality of cylinders, a sleeve fitted within each cylinder and provided with an intake port and an outlet port, a transverse partition in each cylinder between said ports and separating each cylinder into a compression chamber and an explosive chamber, each sleeve being provided with a communicating port which is controlled by the corresponding partition and through which said chambers are, at 30 times, connected, a piston reciprocable in each sleeve, an eccentric bearing, connecting rods pivoted at one end to said bearing and at their other ends to said pistons, through which the pistons are reciprocated by the relative rotation of said cylinders and bearing, means for reciprocating said sleeves, and co-acting impeller blades arranged in opposing series, one series being fixed with respect to the eccentric bearing and the other series being fixed with respect to said cylinders.
10. In testimony whereof I have signed my name to this specification in the presence of two subscribing witnesses.
